UNITED STATES PATENT OFFICE.

JOHN M. GILLIGAN, OF ROCKVILLE, INDIANA.

BELT-BUCKLE.

1,257,841.

Specification of Letters Patent. Patented Feb. 26, 1918.

Application filed April 3, 1917. Serial No. 159,442.

To all whom it may concern:

Be it known that I, JOHN M. GILLIGAN, a citizen of the United States, and a resident of Rockville, in the county of Parke and State of Indiana, have made certain new and useful Improvements in Belt-Buckles, of which the following is a specification.

My invention is an improvement in belt buckles and has for its object to provide a buckle of the character specified, wherein the ends may be quickly and easily connected and detached, and wherein the said ends are yieldingly connected.

In the drawings—

15 Figure 1 is a front view of the buckle.

Fig. 2 is a top plan view.

Fig. 3 is a section on the line 3—3 of Fig. 5 looking in the direction of the arrows adjacent to the line.

20 Fig. 4 is a perspective view of the buckle with the ends of the belt disconnected.

Fig. 5 is a section on the line 5—5 of Fig. 3, and

Fig. 6 is a rear view of the buckle with 25 the ends of the belt disconnected.

In the present embodiment of the invention, the buckle is composed of a channel or U shaped member 1, having at one end a longitudinally extending lug 2, and a second channel or U shaped member 3 is provided, having one end closed as shown, and having at the said end, a longitudinally extending lug 4, which is pivotally connected to the lug 2 by a rivet 5 or the like. The U shaped member 3 is adapted to swing into and out of the U shaped member 1 as shown in Figs. 4 and 5, and the said member 3 has its channel facing downward, that is, the said member is reversed with respect to the member 1.

One of the ends 6 of the belt is connected to the U shaped member 3 and the other end 7 of the belt is adapted to engage between that wall of the U shaped member 1 remote 45 from the lug 2 and the adjacent wall of the U shaped member 3. The end 6 of the belt is connected to the member 3 by a pin and slot connection 7^a and 8. The end 6 of the

belt has a metal clip which is secured to the end thereof, and at the clip, the belt is slotted longitudinally as indicated at 8. The pin 7^a extends transversely between the walls of the U shaped member 3 and springs 11 are arranged between the clip 9 and a cross bar 10 at closed end 14 of the member 3. These springs normally hold the belt end and the member 3 in the position of Fig. 3, but the belt end may yield with respect to the channel shaped member within limits prescribed by the slot 8.

The belt end 7 is provided with a series of openings 12, and one of these openings is adapted to be engaged with a laterally extending pin 13 on that wall of the channel shaped member 3 remote from the lug 2. 65 There is sufficient space between the adjacent walls of the members 1 and 3 of this pin to permit the easy insertion of the belt.

In use the belt is placed about the body with the buckle in front and the channel shaped member 1 is swung down with respect to the member 3, as indicated in Fig. 4, until the belt end 7 may engage with the pin 13. When this is done, the member 1 is swung upwardly into the position of Figs. 70 75 1 and 2, and it will be obvious that the belt ends cannot become disengaged until the member is swung down with respect to the member 3. The belt ends may yield with respect to each other to prevent undue pressure of the body.

I claim:

A belt buckle comprising a pair of channel shaped members, one of the members being inverted and pivotally connected to the other member at one wall thereof to swing within the channel of the same, and being of less width to leave a space between the opposite wall and the said first named member, said first named member having a pin 90 extending laterally toward the last named wall of the second named member, said pin being adapted to engage one end of a belt, the other end being adapted for connection with the first named member.

JOHN M. GILLIGAN.
